UNITED STATES PATENT OFFICE.

AUGUST J. HEINE, OF WAHPETON, NORTH DAKOTA.

KNIFE-SHARPENER FOR BAND-CUTTERS.

SPECIFICATION forming part of Letters Patent No. 738,192, dated September 8, 1903.

Application filed June 7, 1902. Serial No. 110,596. (No model.)

To all whom it may concern:

Be it known that I, AUGUST J. HEINE, of Wahpeton, Richland county, North Dakota, have invented certain new and useful Im-
5 provements in Knife-Sharpener for Band-Cutters, of which the following is a specifica-
tion.

The primary object of this invention is to provide means for sharpening band-cutter knives while the machine is in operation.

A further object is to provide means for sharpening any style or shape of knife while in motion, and adapted particularly for sharpening those whose edges from continued hard 15 usage or by accident have become irregular and crooked.

Further, the invention consists in pivotally supporting the grinding-blocks so that the part to engage the knives will be between the 20 pivots of the blocks and the means for operating the same, to the end that the blocks can be more conveniently adjusted and a better leverage obtained on the cutting edges of the knives.

25 The invention consists generally in providing a series of grinding-blocks of emery or other suitable material adapted to be moved into engagement with the cutting edges of the knives during the operation of the machine and to adjust themselves automatically to the varying shapes, condition, and irregular arrangement of the knives.

Further, the invention consists in the particular means for adjusting the knives, to the 35 end that the proper angle of the grinding-blocks with respect to the knives may be obtained.

Further, the invention consists in the various constructions and combinations, all as 40 hereinafter described, and particularly pointed out in the claims.

In the accompanying drawings, forming part of this specification, Figure 1 is a horizontal section of a portion of a band-cutter casing with my invention applied thereto, the grinding position of the blocks being indicated by dotted lines. Fig. 2 is a similar view showing the straw-guards in position between the knives. Fig. 3 is a vertical section through 45 the band-cutter shaft, showing the position of the sharpening device with respect to the knife. Fig. 4 is a section on the line *y* *y* of

Fig. 3. Fig. 5 is a detail of the grinding-block-operating rod and a plate for holding the same in its extended position. Fig. 6 is 55 a horizontal section of a portion of the band-cutter casing, showing a modified means for supporting the blocks where the band-cutter knives are located above the grain. Fig. 7 is a vertical section of the same. 60

In the drawings, 2 represents a portion of a band-cutter and feeder-casing wherein the band-cutter shaft 3 is mounted in suitable bearings. Upon this shaft I provide a series of knives 4 of the usual construction, separated by sleeves 5 and held together on the shaft by the usual or any preferred means. The edges of these knives soon become dulled in the operation of the machine and it has been customary to stop the machine long 70 enough to sharpen the knives or remove them for that purpose. This operation of course requires considerable time and causes delay in the operation of the machine. To avoid this loss of time and labor in sharpening the 75 knives, I provide means within control of the operator for sharpening the knives simultaneously during their operation. In carrying out my invention I provide a cross-bar 6 near the band-cutter shaft and arrange thereon at intervals a series of brackets 7, which extend beneath said shaft between the pairs of knives thereon. Upon each bracket I prefer to provide a sheet-metal straw-guard 8, that is arched at one end over the band-cutter 80 shaft and secured at two points to said bracket. The free end of each guard extends down a sufficient distance to prevent the straw from being carried around by the knives and wound upon the shaft. Near the cross-bar 6, suitably mounted in bearings in the machine-casing, is a rod 9, having at one end a handle 10, that is adapted to engage any one of a series of depressions 11, provided in a triangular locking-plate 12. The rod 9 passes through a 85 series of slots 13, provided in oscillating arms 14. These slots are of sufficient length to allow the arms to be swung at an angle to said rod to bring them in the proper position for the sharpening-blocks to engage the 100 knives. Each arm is provided with a recess 15, adapted to receive a block of emery or other suitable sharpening material, said block being engaged at one end by a lip 16 and at

90

100

the other by an adjustable clip device 17, by means of which the block may be locked in position. The outer end of each arm 14 is provided with a hole 18 to receive a thimble 19, through which a bolt 20 passes into a slot 21, provided in each arm 7. The bolt 20 being adjustable in said slot permits the sharpening-block to be adjusted at the proper angle with respect to the adjacent knife-blade. To hold the sharpening devices away from the knives, I provide a series of springs 22 on the rod 9. These springs are arranged between each pair of arms and tend to hold them in a position substantially at right angles to the rod 9 and out of engagement with the knives. Between these springs and the arms, at one side thereof, I provide adjustable collars 23, which prevent movement of the arms in one direction on the rod 9, while the springs 22 10 15 20 25 30 35 40 45 with a series of knives, of grinding-blocks pivotally supported between said knives, means for moving said blocks into contact with said knives and holding them in engagement therewith with a yielding pressure, the engaging surfaces of said blocks with said knives being between their supports and said moving means.

5. The combination, with a shaft provided with a series of knives, of grinding-blocks having adjustable pivots, means for swinging said blocks into engagement with said knives and holding them there with a yielding pressure, the engaging surfaces of said blocks with said knives being between their pivots and said swinging means.

6. A sharpening device for band-cutters, comprising supports projecting between the band-cutter knives, arms pivotally connected to said supports near the axis of said knives and adjustable transversely with respect thereto, grinding-blocks carried by said arms and adapted to engage the edges of said knives and means for oscillating said arms to move said blocks into or out of contact with said knives.

7. The combination, with a band-cutter shaft and the knives arranged thereon, of a cross-bar provided near said shaft, a series of brackets provided on said bar and projecting between said knives, a series of arms pivotally connected with said brackets near their free ends, blocks carried by said arms and adapted to engage the edges of said knives and means for oscillating said arms.

8. The combination, with a band-cutter shaft and the knives thereon, of a series of brackets projecting between said knives and

provided with transverse slots, a series of arms having adjustable pivotal connections with said slots, means for oscillating said arms, grinding-blocks carried by said arms and adapted to engage the edges of said knives, the points of contact of said blocks with the knives being between the pivots of said arms and said oscillating means.

9. The combination, with a band-cutter shaft and the knives arranged thereon, of a series of brackets projecting between said knives and provided near their free ends with transverse slots, straw shields or guards carried by said brackets, arms arranged beneath said brackets and having adjustable pivotal connections with said slots, sharpening-blocks carried by said arms and adapted to engage the edges of said knives, a longitudinally-movable rod whereon the outer ends of said arms are loosely mounted, and springs provided on said rod between said arms.

10. The combination, with a band-cutter shaft and the knives thereon, of suitable supports, arms pivotally connected near one end to said supports, grinding-blocks carried by said arms and adapted to engage the edges of said knives respectively, means for swinging said arms to move said blocks into engagement with their knife-edges, and springs provided in connection with said arms and allowing independent movement thereof away from said knives, substantially as described.

In testimony whereof I have hereunto set my hand this 31st day of May, 1902.

AUGUST J. HEINE.
